UNITED STATES PATENT OFFICE.

DEWEY H. BITNEY, OF ALBION, MICHIGAN, ASSIGNOR TO UNION STEEL PRODUCTS COMPANY, OF ALBION, MICHIGAN.

DISPLAY RECEPTACLE.

Application filed May 23, 1925. Serial No. 32,345.

To all whom it may concern:

Be it known that I, DEWEY H. BITNEY, a citizen of the United States, residing at Albion, county of Calhoun, State of Michigan, have invented certain new and useful Improvements in Display Receptacles, of which the following is a specification.

This invention relates to improvements in display receptacles.

10 The main object of this invention is to provide an improved display receptacle in which the bottom may be adjusted to vary the capacity of the receptacle or to incline the bottom as may be desired to facilitate 15 the display of the contents.

Objects pertaining to details and economies of my invention will definitely appear from the detailed description to follow.

20 I accomplish the objects of my invention by the devices and means described in the following specification. The invention is clearly described and pointed out in the claims.

25 A structure embodying the features of my invention is clearly illustrated in the accompanying drawing forming a part of this application, in which:

30 Fig. I is a perspective view of my improved display basket or receptacle with the adjustable tray or bottom in one of its several possible positions.

Fig. II is a fragmentary vertical transverse section with the adjustable bottom shown in full lines.

35 Fig. III is a perspective view of the adjustable bottom support.

In the drawing similar numerals of reference refer to similar parts in all of the views.

40 My improved display basket or receptacle in the embodiment illustrated is of rectangular cross section, the side walls being made up of border or frame members consisting of the top cross member 1 and side members 2 integral therewith extended to provide legs 3, the ends of the wires being bent upwardly and crossed providing braces 4. The side members are connected by the bottom frame member 5.

50 The horizontal slats 6 are secured to the side members 2 and vertical slats 7 are secured to the top cross member 1 and bottom cross member 5. The bottom cross member has inward offsets 8 providing rests for the 55 meshwork bottom 9. These side members

are connected by the strap-like hinge members 10 so that when the bottom 9 is removed the structure may be collapsed.

The adjustable bottom 11 is preferably in the form of a pan or tray and is of such 60 dimensions that it may be adjusted to a horizontal position or to an inclined position within the receptacle. This bottom or tray is supported in its adjusted positions by means of the U-shaped support 12 which 65 is adapted to be inserted through one side of the receptacle, resting on a horizontal slat below it as shown in Fig. I, the ends of its arms having downwardly facing hooks 13 thereon which are engaged over a horizontal 70 slat on the opposite side, thus supporting the pan in an inclined position and at any height desired, the variation, of course, depending upon the spacing of the horizontal slats.

75 The receptacle can thus be readily adjusted for the display of varying quantities of material and the receptacle appears full without regard to the amount displayed. Also, the inclining of the tray or bottom 11 80 facilitates the display of certain articles which may be arranged thereon. If desired, the tray may be supported at the top and filled with water for fresh vegetables such as asparagus, celery, onions, lettuce, 85 radishes, and the like.

For certain purposes the tray may be omitted and the wire bottom adjustably supported in any desired position by the support, or the wire bottom may be adjust- 90 ed as desired and the tray placed thereon.

Having thus described my invention what I claim as new and desire to secure by Letters Patent is:

1. The combination with a wire receptacle 95 having horizontal and vertical slats, of a bottom member adjustable within said receptacle, and a U-shaped bottom member support disposed through one side of the receptacle to rest on a horizontal slat and with 100 its bight portion embracing the vertical slats between the arms and its hooks disposed facing downwardly and engaged with a horizontal slat on the opposite side of the receptacle.

105 2. The combination with a wire receptacle having horizontal and vertical slats, of a bottom member adjustable within said receptacle, and a support extending across the receptacle for adjustably supporting said 110

bottom within said receptacle, said support being adapted to be inserted between the slats and being selectively engageable with slats on opposite sides of the receptacle.

5. 3. The combination with a wire receptacle having open-meshed walls, of a bottom member adjustable within said receptacle, and a support for adjustably supporting said bottom within said receptacle adjustably engageable with slats on opposite sides of the receptacle.

4. The combination with a receptacle having open-meshed walls, of an adjustable bottom member, and a U-shaped support therefor adapted to be inserted through meshes at one side of said receptacle and having hooks on its arms engageable through meshes on the opposite sides of said receptacle.

In witness whereof I have hereunto set my hand.

DEWEY H. BITNEY.
